UNITED STATES PATENT OFFICE.

GEORGE C. KIMMEL, OF CINCINNATI, OHIO, ASSIGNOR TO THE CINCINNATI GRINDER COMPANY, OF CINCINNATI, OHIO, A CORPORATION OF OHIO.

GRINDING-MACHINE.

1,337,139.

Specification of Letters Patent. Patented Apr. 13, 1920.

Application filed April 15, 1918. Serial No. 223,738.

To all whom it may concern:

Be it known that I, GEORGE C. KIMMEL, a citizen of the United States, and residing at Cincinnati, in the county of Hamilton and State of Ohio, have invented a new and useful Improvement in Grinding-Machines, of which the following specification is a full disclosure.

My invention relates to a grinding machine and is more particularly directed to that type known in the art as a "hole grinder."

The object of the invention is to provide a machine of this type with a turn-table tool-head coöperating with devices functioned by the carriage travel, for oscillating the head.

Another object is to provide means for locking the turn-table in normal position, with provisions for disengaging said lock subsequent to a table oscillation to abnormal position.

Another object is to provide a latch control for the turn-table operating device.

In a machine of this type the grinding wheel spindle rotates at high speed and if it is not stopped during the removal of the finished work and the chucking of a new piece and also during the caliper of the work, there is great danger of injury to the operator, by coming in contact with the grinding-wheel.

In the present machine this danger has been eliminated by the provision of an oscillating turn-table which carries the grinding spindle head and which is oscillated to swing the wheel backward and away from the work as the turn-table carriage completes its return travel. The turn-table

is returned to normal position during the first part of a subsequent forward carriage feed and is locked in true alinement for a work engaging operation.

While I have shown this mechanism as applied to a grinding machine, it is obvious that any form of rotary tool or cutter may be substituted for the grinding wheel.

The features of the invention are more fully set forth in the description of the accompanying drawings, forming a part of this specification, in which:—

Figure 1 is a front elevation, partly in section, showing the control mechanism of the grinding spindle turn-table in release position.

Fig. 2 is a top plan view partly in section.

Fig. 3 is a vertical section on line 3, 3, Fig. 2.

Fig. 4 is a vertical section of the upper portion of the machine on line 4, 4, Fig. 1. 60

Fig. 5 is an enlarged detail front elevation of trip control of the grinding spindle turn-table.

Fig. 6 is an enlarged detail section on line 6, 6, Fig. 1. 65

The main elements of the machine comprise a frame, an adjustable head-stock and a tool carriage carrying a turn-table tool-head. The frame consists of a front wall 1, a back wall 2 and end walls 3, 4, forming 70 a box-like structure inclosing and supporting the various drive and speed change elements which may be of any preferred form and which are not herein illustrated or described in detail except in so far as they 75 are correlated to the present invention.

The upper surfaces of the front and back walls 1, 2, form ways 5, 6, upon which the tool-carriage 7 slides, the way 5 being of V-formation and the way 6 of table formation. 80 The head-stock end of the frame is provided with transverse ways 8, 9, upon which slides a head-stock carriage 10. This head-stock carriage is translated by a hand wheel 11, through any suitable feed screw 85 mechanism and the head-stock 12 is carried on a rotatable plate 13, adapted to be adjusted by a hand wheel 14 to aline the head-stock spindle 15 parallel with the main slide-ways 5, 6, for straight grinding or 90 at an angle thereto for taper grinding. The head-stock spindle may be provided with a suitable chuck 16 for supporting the work and is driven in any suitable form of drive mechanism. 95

The present invention is not directed to any specific form of head-stock, therefore only such illustration and description thereof is herein presented as will promote a thorough understanding of the general operation of the machine. 100

The tool carriage 7 slides upon the ways 5, 6, and has secured to its under surface a bracket 18, (see Fig. 3), depending between the front and back frame walls 1, 2. 105 Secured to the bracket 18 is a feed rack 19 meshing with a pinion 20 which is fixed to the inner end of a shaft 21. The shaft 21 is journaled in the front wall 1 and is provided at its outer end with a manually operated hand wheel 22.

A turn-table tool-head 25 is journaled on

the carriage 7, it being laterally retained by a beveled journal ring 26 fixed to the carriage and held in close contact with the surface of the carriage by a split retaining 5 collar 27 secured to the carriage by screws 28 (see Fig. 2). In the bearing 29 of the tool-head is journaled a grinding wheel spindle 30 having an overhanging drive pulley 31 fixed to one end, the opposite end 10 carrying a grinding wheel 32. A housing 33 incloses a drive pulley 31 and the spindle 30 is driven by a belt 34 engaging over the pulley 31 and leading downward into the interior of the frame. The belt is 15 guided by two guide rollers 35, 36, journaled on the turn-table and engages over a drive wheel 36 secured to a power shaft 37 journaled in the lower portion of the frame. One of the belt runs is entrained around a 20 pair of belt tightening pulleys 38, 39, carried by a pair of rods 40, 41, depending from the carriage 7.

The turn-table tool-head 25 is normally locked in position to insure a true parallel 25 alignment of its spindle 30 with the ways 5, 6, of the frame, by a spring pressed plunger 45, (see Figs. 1, 2, 5). The plunger 45 is mounted to slide in a vertical bore in the carriage 7 and bracket 18 and is provided 30 with a tapered nose, adapted to engage in a correspondingly tapered lock recess 46 in the turn-table 25. To guard against the wearing of the parts to a point of imperfect operation and to facilitate their convenient removal, I form the recess 46 in a 35 steel collar insert 47 seated in the table 25 against a washer 48. The washer 48 has a screw-threaded bore into which a correspondingly screw-threaded tool may be engaged to force or pull out the collar insert 40 47. The upper portion of the vertical bore in the carriage is also provided with a steel sleeve 49 as a protection against undue wear. The plunger 45 is notched as at 50 to 45 form a beveled shoulder 51, which is engaged by the beveled nose 52 of a plunger operating bar 53 as the carriage 7 is returned to normal position. The rod 53 is fixed to a bracket 54 secured to the end wall 50 54 of the frame and is guided in a channel 55 formed in the carriage 7.

In Fig. 1, the plunger 45 is shown in retracted position unlocking the turn-table tool-head 25. A further return movement 55 of the carriage will not affect the plunger but when the carriage is fed toward the work, the plunger 45 will become disengaged from the bar 53 and be spring-pressed upward into the lock recess 46 of the turn-table. 60

To oscillate the tool-head to swing the grinding-wheel backward when the carriage 7 nears the end of its return travel, I provide a toothed rack bar or oscillator 60 slidably retained on the front upper surface of

the carriage by the retaining collar 27 and operating in a channel 61 therein. The teeth of the rack bar 60 mesh with teeth formed on the peripheral edge of the turn-table 25 and the opposite end of the bar 60 70 is adapted to contact with an abutment surface 62 of the stationary bracket 54 near the end of the return travel of the carriage 7 to hold the bar 60 stationary, after which the final portion of said return travel of the 75 carriage will cause the turn-table tool-head 25 to be oscillated.

For holding the rack-bar 60 stationary during the first part of the forward carriage feed, to restore the turn-table to normal position, I provide a retaining device or gravity latch 70 which is pivoted on the bar 60 and has a hooked end 71, adapted to engage a projection 72 formed on the bracket 54, (see Fig. 5). The opposite weight end of 85 the latch 70 is provided with a beveled shoulder 73 and a beveled nose stud 74 fixed on the carriage 7 in alignment with the shoulder 73 of the latch 70 is adapted to engage and rock the latch to disengage its 90 hooked end 71 from the projection 72. The stud 74 is so located on the carriage 7 that its engagement with the latch will take place immediately after the turn-table 25 is restored to normal position and the abutment surface 62 of the bracket 54 is so located as to allow the turn-table lock plunger 45 to be withdrawn from the table engagement by the plunger operating bar 53, before said abutment surface arrests the rack- 100 bar 60.

To limit the downward movement of the weight end of the latch 70, so that it will not drag on the carriage 7, I provide a stud 80 fixed on the rack-bar 60 and projecting 105 into an enlarged bore 81 in the latch 70.

To relieve the turn-table lock plunger 45 of the strains incident to a grinding operation, I provide an abutment arm 85 extending from the turn-table 25 and engaging an adjustable stop stud 86 mounted in a leg 87 projecting upwardly from the carriage 7.

The circulating lubricating system comprises a supply reservoir casing 90 projecting 115 from the back frame wall 2 and forming therewith a supply reservoir 103 having a cover plate 91. Supported on the cover plate 91 and depending into the supply reservoir is a centrifugal pump 92 having a 120 discharge conduit 93, extended upwardly through said cover and connecting with the distributing conduits 94, 95. The conduit 94 is supported in a bracket 96 adjustably attached to the cover plate 91 and conveys 125 the lubricant to flow on the exterior surface of the work. The conduit 95 is supported in a bracket 97 adjustably attached to the head-stock carriage 10 and extends through the hollow head-stock spindle 15, conveying 130

the lubricant to flow on the interior surface of the work.

The pump 92 is driven by a belt 98 engaging a belt pulley 99 on a power shaft 6 100 and entrained over a pair of guide pulleys 101, 101, and around a pulley 102 fixed to the pump shaft.

Within the interior of the main frame adjacent the supply reservoir 103, I provide a 10 settling basin 104 formed by the front and back frame walls 1 and 2 and by partition walls 105, 106, 107. An overflow aperture 108 leading into the supply reservoir 103 is formed in the back wall 2 and supported 15 near the top of the frame over the settling basin is a strainer plate 109. The forward end of the tool carriage 7 is provided with a marginal wall 110 terminating at a drain spout 111 and the upper surface slopes toward 20 said spout to drain the lubricant flowing thereon into the settling basin.

In machines of this character it is desirable that some means be provided for protecting the main slide-ways 5, 6, from injury by grinding or otherwise, and in the present invention I have provided inwardly and downwardly inclined cover plates 115, 25 116, extended the full length of the ways. These plates are secured to the front and 30 back frame walls 1, 2, and are of sufficient width to fully cover their respective slide-ways, serving also to entrain the lubricant into the settling basin 104.

Having described my invention, I claim:

35. 1. In a machine of the class described comprising a bed and a reciprocating tool carriage in combination therewith, an oscillating tool-holder journaled on the carriage, means on the bed, carriage and tool-holder 40 coördinately operated by the carriage travel, to aline the tool in work engaging position during the forward carriage feed and to swing the tool to inoperative position during the retractive carriage travel, and means for 45 locking and releasing the tool-holder.

2. A machine of the class described comprising a frame, a carriage slidably mounted thereon, a turn-table tool-head journaled on the carriage, means for translating the carriage, a device for oscillating the tool-head by the translation of the carriage, and a work carrying head mounted upon said frame translatable transversely to said carriage and carrying a rotatable work support 55 spindle.

3. A machine of the class described comprising a frame, a carriage slidably mounted thereon, a turn-table tool-head journaled on the carriage, means for translating the carriage, a device for oscillating the tool-head, means for locking the tool-head against oscillation, and a device for disabling said lock means previous to a tool-head oscillation.

4. A machine of the class described comprising a frame, a slideable carriage, a turn-

table tool-head journaled thereon, means for translating the carriage, separate means for oscillating the tool-head, a lock for the tool-head, devices for disabling said lock for subsequent tool-head oscillation, and a work 70 carrying head mounted upon said frame translatable transversely to said carriage.

5. A machine of the class described comprising a frame, a carriage slidably mounted thereon, a turn-table tool-head supported on 75 the carriage and provided with a lock recess, a lock plunger normally engaging said recess, a plunger operating member fixed on the frame, a device for oscillating the tool-head, and means for translating the carriage 80 to retract the lock plunger from engagement with the lock recess for subsequent tool-head oscillation.

6. A machine of the class described comprising a frame, a carriage slidably mounted 85 thereon, a turn-table tool-head supported on the carriage, a tool-head oscillator carried by the carriage and adapted to engage the frame during a retractive translation of the carriage to oscillate the tool-head, a retaining device for arresting the oscillator during a reverse carriage translation to normalize 90 the tool-head, means for disabling said retaining device when the tool-head is normalized, and means for translating the carriage.

7. A machine of the class described comprising a frame, a carriage slidably mounted thereon, a turn-table tool-head supported on 100 the carriage, a tool-head oscillator, a lock for the tool-head, a retaining device for the oscillator, a trip for the retaining device, and means for translating the carriage.

8. A machine of the class described comprising a frame, a carriage slidably mounted 105 thereon, a turn-table tool-head supported on the carriage, means for translating the carriage, a lock for retaining the tool-head in normal position, and devices functioned by the carriage translation for first unlocking 110 and subsequently rotating the tool-head during a retractive carriage translation and for first normalizing and subsequently locking the tool-head during a reverse carriage 115 translation.

9. In a machine of the character described, a base frame, a work-carrying head mounted upon said base frame or casing translatable upon said frame toward and from said work-carrying head, a tool supporting head mounted on said carriage and having a spindle carrying a rotary tool and driving means therefor, said tool-holding head mounted for oscillation on an axis angular to the axis of the tool spindle, and 120 means for oscillating said tool supporting head.

10. In a machine of the character described, a rail base frame, a work-carrying head mounted upon said base frame, having 125

- a rotatable work-holding spindle, a carriage translatable on said frame toward and from the work-holding spindle, longitudinal with the axis of said spindle, a tool supporting head mounted on said carriage and having a spindle carrying a rotary tool and driving means therefor, the spindle normally coaxial with said work holding spindle, said tool holding head mounted for oscillation on an axis angular to the axis of the tool spindle, for swinging the spindle horizontally angular to the axis of said work holding spindle, and means for oscillating said tool supporting head.
- 15 11. In a machine of the character described, a base frame, a work carrying head mounted upon said base frame or casing translatable upon said frame toward and from said work carrying head, a tool supporting head mounted on said carriage and having a spindle carrying a rotary tool and driving means therefor, said tool holding head mounted for oscillation on an axis angular to the axis of the tool spindle, means for oscillating said tool supporting head, and means for locking said tool supporting head to the carriage against oscillation.
- 20 12. In a machine of the character described, a rail base frame, a work carrying head mounted upon said base frame, having a rotatable work holding spindle, a carriage translatable on said frame toward and from the work holding spindle, longitudinal with the axis of said spindle, a tool supporting head mounted on said carriage and having a spindle carrying a rotary tool and driving means therefor, the spindle normally coaxial with said work holding spindle, said tool holding head mounted for oscillation on an axis angular to the axis of the tool spindle, for swinging the spindle horizontally angular to the axis of said work holding spindle and said rotary tool to a safety zone, and mean coöperating with said tool supporting head during the carriage travel within retracted limits of the carriage travel for automatically alternately swinging said tool supporting head.
- 25 13. In a machine of the character described, a base frame, a carriage translatable on said frame, a tool supporting head mounted on said carriage having a spindle carrying a rotary tool and driving means therefor, a transmission supporting frame depending from and carried by said carriage, transmission means carried by said supporting frame in driving connection with said tool driving means of the spindle.
- 30 14. In a machine of the character described, a base frame, a work carrying head mounted upon said base frame or casing, translatable upon said frame toward and from said work carrying head, a tool supporting head mounted on said carriage and having a spindle carrying a rotary tool and driving means therefor, said head mounted for oscillation to swing the rotary tool to a safety zone, and belt transmission means dependingly supported from and carried by said carriage in driving connection with said rotary tool driving means and housed within said hollow base frame.
- 35 15. In a machine of the character described, a hollow base frame, a carriage translatable on said frame, a tool supporting head mounted on said carriage and having a spindle carrying a rotary tool and driving means therefor, said tool holding head mounted for oscillation on an axis angular to the axis of the tool spindle, a rack member coöperating with said tool supporting head for oscillating the same, automatically operated at a predetermined point of the retreat movement of said carriage.
- 40 16. In a machine of the character described, a base frame, a work carrying head mounted upon said base frame or casing translatable upon said frame toward and from said work carrying head, a tool supporting head mounted on said carriage and having a spindle carrying a rotary tool and driving means therefor, the spindle normally coaxial with said work holding spindle, said tool holding head mounted for oscillation on an axis angular to the axis of the tool spindle, for swinging the spindle horizontally angular to the axis of said work holding spindle and said rotary tool to a safety zone, and mean coöperating with said tool supporting head during the carriage travel within retracted limits of the carriage travel for automatically alternately swinging said tool supporting head.
- 45 17. In a machine of the character described, a base frame, a carriage translatable on said frame, a tool supporting head mounted on said carriage having a spindle carrying a rotary tool and driving means therefor, a transmission supporting frame depending from and carried by said carriage, transmission means carried by said supporting frame in driving connection with said tool driving means of the spindle.
- 50 18. In a machine of the character described, a base frame, a carriage translatable on said frame, a tool supporting head mounted on said carriage having a spindle carrying a rotary tool and driving means therefor, a transmission supporting frame depending from and carried by said carriage, transmission means carried by said supporting frame in driving connection with said tool driving means of the spindle.
- 55 19. In a machine of the character described, a base frame, a carriage translatable on said frame, a tool supporting head mounted on said carriage having a spindle carrying a rotary tool and driving means therefor, a transmission supporting frame depending from and carried by said carriage, transmission means carried by said supporting frame in driving connection with said tool driving means of the spindle.
- 60 20. In a machine of the character described, a base frame, a carriage translatable on said frame, a tool supporting head mounted on said carriage having a spindle carrying a rotary tool and driving means therefor, a transmission supporting frame depending from and carried by said carriage, transmission means carried by said supporting frame in driving connection with said tool driving means of the spindle.
